CORSET

Eva Klein, Brooklyn, N. Y.

Application October 3, 1934, Serial No. 746,725

5 Claims. (Cl. 2—37)

This invention relates to corsets, an object of the invention being to provide a corset having elastic material extending around the back and at least portions of the sides of the garment, which elastic is located below the waist-line of the garment and stretches up and down, so that while the corset gives the proper shape and support to the body this elastic material permits the corset to stretch vertically and compensates for the movement of the body especially when sitting down, so that the corset is comfortable at all times to the wearer.

A further object is to provide a corset of this character in which the corset will always lie smoothly on the body and yet permit movement of the body without constriction.

With these and other objects in view, the invention consists in certain novel features of construction and combinations and arrangements 20 of parts, all of which will be more fully herein-after described and pointed out in the claims.

In the accompanying drawing—

Figure 1 is a perspective view illustrating my improved corset in position on the body of the 25 user;

Figure 2 is a rear view of the corset showing the same extended;

Figure 3 is an enlarged view in vertical section on the line 3—3 of Figure 2; and

Figure 4 is a fragmentary enlarged view in section on the line 4—4 of Figure 2.

The reference character A indicates generally my improved corset which is mainly of inelastic material which may be strengthened and reinforced in any approved manner and which is, of course, made of the proper shape suitable for the body on which it is to be used.

This corset A is provided with an inner belt 1 which is also of inelastic material, and the corset 40 A and belt 1 are provided at their front edges with suitable fastening devices 3 to secure the belt and corset around the body.

While the corset is mainly of inelastic material, it may, of course, be provided with suitable elastic inserts 4 and may be made in accordance 45 with any pattern desired.

The corset A is provided around the back and sides thereof with a section of elastic material 5. This section 5 is secured at its edges in an opening suitably formed in the corset to receive the same, and a line of stitching 6 extends throughout the length of the elastic section 5 and sewed to the belt 1. This elastic section 5 may be made of any number of pieces and is preferably such 55 that it stretches only in an up and down direc-

tion around the body. In the particular construction illustrated, I have shown this elastic section as of three pieces, one piece 7 extending throughout the back of the corset and at its end slightly overlapping shorter pieces 8 are extended around the sides of the garments. This elastic section, as shown in Figures 1 and 2 of the drawing, terminates short of the front edges of the garment, but as indicated in Figure 5 of the drawing this elastic section may extend to 10 the front edges of the garment so that the elastic is all around the garment.

It is to be distinctly noted that the elastic section 5 is appreciably narrower than the belt 1 and is located below the waist-line of the garment. By reason of the fact that the elastic is appreciably narrower than the belt any stretching of the elastic will not cause the elastic to extend above or below the belt, and hence will not come in contact with the flesh of the user. 20 However, there will be sufficient elasticity to compensate for all ordinary movements of the body and give ease and comfort thereto.

It will, furthermore, be noted that the stretching of the elastic in a vertical up and down direction is above and below the line of stitching 6 so that in some movements only the lower portion of the elastic will be caused to stretch and in other movements only the upper portion of the elastic will stretch, and then in only extreme 30 movements of the body both portions of the elastic will stretch.

It will be understood that I do not wish to limit myself to any particular form of the elastic; that is to say, any particular number of pieces constituting the same, but that regardless of the number of pieces the elastic section will be a continuous member extending around the back and sides of the garment below the waist-line and over the belt, which is appreciably wider 40 than the elastic so that the elastic cannot stretch far enough in normal use to extend above or below the belt.

It will also be noted that the elastic section 5 is widest at the center of the back of the garment 45 and tapers toward both ends; furthermore, it will be noted that the elastic is of such shape that its lower edge is curved in the arc of a circle, while its upper edge is somewhat curved yet is much straighter than the lower edge. This shape 50 is believed to be a preferable one so as to properly conform to the shape of the body, as clearly indicated in Figure 1 of the drawing.

While I have illustrated what I believe to be the preferred embodiment of my invention, it is 55

to be distinctly understood that various slight changes may be made with regard to the form and arrangement of parts without departing from my invention, and hence I do not limit myself to 5 the precise details set forth but consider myself at liberty to make such changes and alterations as fairly fall within the spirit and scope of the claims.

What I claim is:

- 10 1. In combination, a corset, an inner belt of inelastic material, and an elastic section in the corset extending around the back and sides of the corset over the belt, said elastic section and said belt secured together intermediate their upper and lower edges, said elastic section being appreciably narrower than the belt.
- 15 2. In combination, a corset, an inner belt of inelastic material, an elastic section in the corset extending around the back and sides of the corset over the belt, said elastic section being appreciably narrower than the belt, and a line of stitching extending longitudinally through the elastic material and through the belt securing the belt directly to the elastic material.
- 20 3. In combination, a corset, an inner belt of inelastic material, an elastic section in the corset extending around the back and sides of the corset over the belt, said elastic section being appreciably narrower than the belt.
- 25

ciably narrower than the belt, and a line of stitching extending longitudinally through the elastic material and through the belt securing the belt directly to the elastic material, said elastic material located in the corset appreciably below the waist-line of the corset. 5

4. In combination, a corset, an inner belt of inelastic material, and an elastic section in the corset extending around the back and sides of the corset over the belt, said elastic section and 10 said belt secured together intermediate their upper and lower edges, said elastic section being appreciably narrower than the belt, said elastic material stretching only in an up and down direction. 15

5. In combination, a corset, an inner belt of inelastic material, and an elastic section in the corset extending around the back and sides of the corset over the belt, said elastic section and said belt secured together intermediate their 20 upper and lower edges, said elastic section being appreciably narrower than the belt, said elastic material widest at its central portion, which is at the center of the back of the garment, and decreasing in width from its central portion to 25 both ends.
